UNITED STATES PATENT OFFICE.

EDWIN R. PROCTER, OF WASHINGTON COURT-HOUSE, OHIO.

CORN-PLANTER.

SPECIFICATION forming part of Letters Patent No. 426,212, dated April 22, 1890.

Application filed January 30, 1889. Serial No. 298,149. (No model.)

To all whom it may concern:

Be it known that I, EDWIN R. PROCTER, of Washington Court-House, Fayette county, Ohio, have invented a new and useful Improvement in Corn-Planters, of which the following is a specification.

My improvements are designed for what are known as "sulky" corn-planters—such as are adapted to plant several rows simultaneously, either in "hills" or in "drills," and to be drawn over the ground by animal-power, the driver sitting upon the machine; but my improvements are more particularly designed to improve Procter's corn-planter, patent dated January 5, 1886, No. 333,547, in which device the seed-delivery is operated by projections or tappets upon a shiftable clutch-plate capable of being coupled to one of the ground-wheels and provided with automatic markers and means whereby the ground-delivery is rendered capable of being adjusted to exact coincidence with the marking action.

The objects of my improvements are, first, to provide auxiliary or companion hill-markers to those on the tappet side of the machine, so that when turning at the end of a "through" there will be "marker-prints" on the ground alongside of the tire-tracks of both bearing-wheels to guide the operator instead of one track only having such prints; second, to provide means by which the two ground-wheels can be made at will to rotate at one and the same speed, so that auxiliary markers clutched fast to one wheel and in alignment with those on the opposite or tappet wheel cannot get ahead—*i. e.*, rotate faster than the markers clutched to wheel upon opposite or tappet wheel, and vice versa; third, to provide means to lessen the jar consequent upon the tappets in the course of revolution striking in succession the heel of seed-delivery rock-shaft; fourth, to improve the furrow-opening and seed-covering devices and at the same time lessen the horse motion; fifth, to provide an improved axle; sixth, to provide an improved axle-stock and planter-frame; seventh, to provide an improved marker.

In the accompanying drawings, Figure 1 is a rear view, part sectional, part elevation, showing the two-part or divided axle for hill-planting in its non-effective condition, (*i. e.*,

with clutches of axles open,) the seed-delivery-operating clutch-plate with its hill-markers, and the auxiliary hill-marker clutch. Fig. 2 is an elevation of the auxiliary hill-marker clutch. Fig. 3 is an elevation of the heel of rock-shaft and a tappet with an anti jar or friction roller in section. Fig. 4 is a top view of the machine in working condition, except that the axle-clutches are disengaged. (They should be engaged for hill-planting, while for drill-planting it is immaterial, there being no hills to mark.) Fig. 5 is my improved marker. Fig. 6 is a longitudinal section with the drag bars and their attachments in the operative position. Fig. 7 is a section through an axle-journal. Fig. 8 is a section through the abutting ends of axles, showing the axle-clutches open or disengaged. Fig. 9 is a longitudinal section with the drag-bars and their attachments raised and fastened into the non-operative position.

A may represent any suitable frame having the supplementary transverse bar A', fastened by the clips a" a" to the axle-journals 75 Q Q', attached to opposite ends of the axle-stock A''. The frame A is supported by the two-part axle B B' on the ground-wheels C C', fast on the parts B and B', respectively, and is provided with any suitable or customary means D for attachment of the draft-animals. The said frame A has attached in rear of the axle three equidistant seed-boxes G G' G'' (the latter is not shown, but is a counterpart of G) attached also to bar A'. 80 The said boxes have suitable seed-delivery slides H, operated as shown and described in Procter's patent of January 5, 1886, No. 333,547, which coact with the adjacent mechanism to deliver the seed to the hill through 85 the receiving ends K of the furrow-openers L and in rear of the latter. The shoes L are fastened between the drag-bars N N at their forward ends by the bolts L', and at their rear ends are suspended between the ends of 90 the straps P, attached to bars N N, and are made fast to said straps P by the bolts O, and are capable of vertical adjustment in the series of holes o in the ends of said straps P. 95 Suspended loosely on the bolt r' between the forward ends of bars N N and in advance of shoe L are the hangers N' N', having at their

top and rear end the friction-roller R', rotating on the bolt r'' , joining the top ends of said hangers. At the lower or forward ends of said hangers is the rolling cutter R, rotating on its axle-bolt r . Hinged to said bolt r , and straddling the top or forward portion of cutter R, is the fork N'', whose tanged end passes loosely through the staple n' , fast on the front transverse bar of frame A, and is provided at its extremity, which is threaded, with the nut n'' , by means of which the height (or depth) of cutter R from top of ground may be adjusted. The fork N'' serves also as a scraper to the cutter R to remove dirt from the cutting-edge of the latter.

The drag-bars N N are attached at their forward ends in any suitable manner to front of frame A. At their rear ends, which are preferably of unequal length, they are provided with the covering-blades S S, bolted through adjustable clamps 19 19 to the ends of bars N N.

At the rear end of the frame A is the drag-lifting bar U' and the wheel-scraper bar S', journaled in the boxes u'' u'' and u''' u''' , respectively. The drag-lifting bar U' has the lever U and the equidistant arms $u' u' u'$, having the depending chains T T T fastened conveniently, one chain to each drag-bar.

Loosely attached by the eyebolt c to the longitudinal brace A'', connecting transverse bars A' and A'', is a locking-bar U'', having the series of notches c'. A pin u on lever U, being engaged in one of these notches, serves to maintain the drag-bars in the elevated condition shown in Fig. 9.

As the operator raises the drag-bars from the ground the friction-rollers R' on the top and rear ends of cutter-hangers N' N' of the several sets of drag-bars are brought simultaneously into contact with the undersides of the depressing-bars a a' a, attached to frame A, thus causing the upper rear ends of said hangers to move automatically back along the under side of said bars a a' a, thus raising up and throwing forward the lower ends of said hangers, and consequently the rolling cutters R attached thereto.

The scraper-bar S' has at opposite ends the blades S'' S'' and is provided intermediate with a lever S''', having the lip l. The said lip, by engaging one of the series of notches inside the rack S''', attached to machine-frame, serves to hold the scraper-blades in their operative position on the wheel-tires, as in Fig. 9.

My improved axle is preferably formed from a hollow cylinder or tubing, and is a two-part axle B B', capable of revolving as one, journaled in axle-boxes Q Q', attached to opposite sides of frame A. Upon the outer and cylindrical ends of these fixed boxes are sleeved the slideable clutch-plates W and W', respectively, the former carrying the tappet mechanism and adjacent hill-markers, the latter (or W') the auxiliary hill-markers only. The axle-boxes Q Q' have on their top faces

the blocks B'' B''', respectively, the said boxes and blocks being bolted together and to the axle-stock A'' by the bolts S S' S'' S''', said bolts S and S''' also serving to fasten the hinges 16 and 17 of the rock-shaft 5 to the top side of axle-stock A''. In addition to the main bearings q q the axles B B' are provided with the supplementary bearings q' q' at inner ends of boxes Q Q' to steady the axles, as well as to afford bearings to axle-collars b b', fastened by set-screws or suitable keys to axles B B', respectively, so as to prevent the abutting ends of axles from moving outward when in motion. At the base of axle-boxes, where they rest on the frame A, are the perforated lugs t t, lapping down on the outsides of said frame and adapted to contain the threaded ends of the truss-rod T', said ends being fitted with nuts, so as to adjust the tension of said rod. The combination of the axle-stock A'', fastened at its ends to the boxes Q Q', with the rod T' likewise fastened, forms a light and stiff trussed girder, to which the stock A'' and the rod T' are the top and bottom chords, respectively.

The seed-delivery-operating clutch-and-tappet mechanism in the present device is in the main the same as in Procter's patent, No. 333,547, above mentioned, except that the slideable clutch-plate W, which in the above patent moved upon a stationary axle, in the present device is sleeved upon the cylindrical outer end of a stationary axle-box Q, the axle now revolving and the ground-wheel with it.

Convenient to the operator are the levers Z Z, hinged to the ends of axle-stock A'' and provided at their lower and forked ends with the links Y, connecting with the yokes X, loosely seated in circumferential grooves in the hubs of clutches W and W', by means of which the said slideable clutches W and W' may be moved upon the cylindrical outer ends of the boxes Q and Q', respectively, in or out of engagement with the fixed clutch-plates V and V' on the ground-wheels. The levers Z Z have the gravity-latches z z, capable of engagement in the notches 1 1 of the racks 2, so as to hold the slideable clutches W and W' either in or out of engagement with the fixed clutch-plates V and V'. The clutch-plate W has an annular series of equidistant holes w for attachment of any desired number of tappets 3 at equal distances around said plate.

In the present device the parts are so proportioned that four tappets operate to discharge grain at the prescribed distance between consecutive hills and in the same manner for hill-planting as in Procter's patent, No. 333,547, except that a series of friction-wheels 3' are fitted on the tappets 3, so that the jar consequent upon the tappets in the course of revolution striking in succession the heel 4 of the rocker 5 is softened.

Provision exists in the present device, as in my patent, No. 333,547, for attachment of sufficient numbers of tappets and rollers for drill-planting.

- The hill-markers 12 are preferably fastened tightly on the ends of metallic tubes 13, which are attached near their other ends to the faces of the clutch-plates W and W' by clips 14. 5 By loosening said clips the tubes 13 can be readily adjusted in or out from the axle, the said clips being loosened by unscrewing the nuts fitted to the threaded ends of clips on the backs of clutch-plates.
- 10 In operating the machine, as described in Procter's patent, No. 333,547, above mentioned, hill-markers 12 on slideable clutch W are provided to indicate the places of alternate hills, so as to enable the operator to see where seed 15 has been dropped and by so doing bring the droppings of each successive through in alignment with those of its predecessor. I find hill-markers on one side only inconvenient, because when the operator has turned to 20 the right (he cannot always turn to the left) at the end of a through, and has started the machine down another through, the marker-prints (on the ground) last made in the finished through are so far to one side of 25 the operator as to be hardly distinguishable by him from the driver's seat. Therefore I provide in the present device a slideable clutch-plate W', with hill-markers 12, similar to those on plate W, thus to afford prints on 30 the ground alongside of both wheel-tracks. I find in practice, also, that when the wheels C C' on the opposite sides of the machine were allowed to run free and independent of each other the wheel carrying the tappet 35 mechanism would run slower than the opposite wheel, inasmuch as the striking of tappets on the heel of rock-shaft retards very perceptibly the tappet-bearing wheel. In other words, the "no-tappet" wheel out-runs 40 the "tappet-wheel," and consequently the prints made on the ground by the no-tappet wheel are, soon after the machine starts from one end of the field, out of alignment—i. e., in advance of those made by the tappet-wheel.
- 45 To obviate this inequality of revolution, I fasten the ground-wheels C C', through their hubs, by the pins 15, to the parts B B', respectively, of the revolving axle journaled in the boxes Q Q'.
- 50 Near the transverse center of the machine where the two parts of axle abut, are attached the toothed clutches 7 and 8, the former fastened by the pin E on axle B, the latter (or 55 8) slideable lengthwise of axle B', but yet held to one place, so as to revolve with said axle, by the key E', fast in axle, and whose ends projecting beyond the periphery of axle are inclosed in key-slots y in the clutch 8. The clutch 8 is held engaged with clutch 7 by 60 the helical spring b''. The teeth of these axle-clutches 7 and 8 mesh, and when the teeth of clutch 8 are held engaged with those of clutch 7 the two-part axle B B' becomes as one piece, revolving in the boxes Q Q' 65 on opposite sides of the machine, with the wheels C C' fast upon it. In operation, as in hill-planting, where it is desired to have the

hill-markers on the opposite sides of the machine (after they have been set into line with each other) rotate in unison and thus 70 preserve the alignment made at the start, the two-part axles are locked together, as above described, and when the end of the through is reached the operator, pulling toward himself the top end of forked lever f, 75 which is hinged to axle-stock A'', can disengage the clutch 8 from its companion 7, so that the two parts of the axle, and consequently the ground-wheels, are free to revolve independently—i. e., one wheel can roll back 80 while the other rolls forward—and thus the machine can be readily turned in another direction. The lever f has its lower end forked to engage the groove g of clutch 8, and is provided near its top end with a projecting pin 85 f', which is capable of being engaged by the bent shoulder of the gravity-latch f'', hinged to A'', thus holding the clutch 8 in the inoperative position shown.

Near the transverse center of the axle-stock 9c A'' is fastened a vertical strut T'', forked at its lower extremity to receive the truss-rod T' and adapted to serve as a supplementary support to the axle. The seat-upright F', attached at its lower end to middle transverse 95 bar of frame A, carries the seat F, adjustably attached on its upper end, and is provided at said end with lateral braces i i, attached at their lower ends to bar A'. Attached to the middle bar of frame A is the foot-rest F'', fitted with the transversely-sliding hook F''', which, when hooked over the inner end m' of marker M, holds said marker in its operative position on either side of the machine. Said marker consists of a pole M, of suitable length, 105 having a fixed runner M' at one end and an eyebolt m fastened intermediate between the ends. In operation, when said eyebolt is dropped over the pin M'' on either side of machine, the runner M' being on the ground, 110 the hook F''', engaging the end m' of marker, holds the latter in its operative condition, yet affords the play required by the runner M' moving or floating over rough ground-surfaces. With this improved marker M, I avoid 115 all necessity of the operator getting off of the machine to transfer the marker from side to side of the frame, as is usual where there is a rope or other attachment from runner M' or from pole M forward to the horses or the front 120 of the machine-frame.

When not in use, the marker M, being disengaged from both the hook and the pin, may be carried lying crosswise of the machine. By tightening the nuts fitted on the threaded 125 ends of truss-rod T' the strut T'' on the said rod and attached to the axle-stock can be forced upward, so as to correct any sagging down of said axle-stock, and therefore of the axle connected with it.

The rolling cutters R when in the ground serve, from the lateral resistance they offer, as stays or rudders to prevent the oscillation from side to side of the machine whenever

the horses fail to step or pull in unison. They are more effective for this purpose in proportion to their proximity to front of the machine-frame. The use of friction-rollers 3' on the tappets 3 not only softens the jar, but the wear on the working-face of heel 4 is lessened.

The use of a tubular form of axle affords the greatest strength in proportion to weight of material.

10 A modified form of my axle-boxes would be to omit, outside of the dotted line, Fig. 7, the cylindrical outer ends *q q* of the boxes *Q Q'*, and what then would be the outer ends of *Q Q'* would serve as bearing for the axle, in which case the slideable clutch-plates *W* and *W'* would be sleeved directly on the (now exposed to view) revolving axle.

15 A modified form of attachment of tubular arms 13 to the clutch-plates would be by means of set-screws, the inner or axle ends of said arms being inserted as far as required in suitable bearings integral with said plates and the said screws tightened. The axle *B B'* is journaled in the vertical strut *T*. Therefore an adjustment of said strut adjusts the said axle.

20 I am aware that a grain-drill (Shephard, December 2, 1879, No. 222,316) having a two-part revolving axle carrying fixed wheels has been provided with mechanism (pawl and ratchet) which, while it did not compel equal revolution of the said wheels, was so arranged that the revolving action of either half-axle, unaffected by the other half, propelled a seed-delivery-actuating sleeve common to both

25 axles when the machine was in motion in any direction. I am aware, also, that a sulky-harrow (Rix, November 21, 1882, No. 267,718) has been provided with a "truss-brace" "to ob-

30 viate the danger of the frame or the front and rear beams of same warping or springing." I am aware, also, that a corn-planter (Vaughan, October 25, 1870, No. 108,656) having an un-

35 divided axle journaled "in boxes" at its ends and carrying "loosely-hinged" wheels has been provided with clutch mechanisms "fitted upon the axle" (splined, presumably) and adapted to fasten at will to the respective ground-wheels, said clutch mechanisms being

40 fitted with radial arms provided with hill-marking and seed-actuating delivery ends, and arranged so that the turning of the axle by hand will turn the ends of said arms forward or back, (*i. e.*, when the said clutch mecha-

45 nisms are unlocked from the wheels.) I am aware, also, that a corn-planter (Procter, January 5, 1886, No. 333,547) has been made with seed-delivery and hill-marking operating clutch-and-tappet mechanism attachable to a

50 ground-wheel pivoted on a fixed axle, the hill-marking being confined to one side of the machine. I am aware, also, that a seeding-machine (Myers & Cotton, February 24, 1885, No. 313,013) provides a lifting-lever which

55 has a bearing-arm carrying a lifting-chain, said chain not being directly attached to the parts to be lifted, but to an arm by which a

rock-shaft carrying other arms is actuated to lift the drag-bars. I am aware, also, that a grain-drill (Koellér, January 22, 1884, No. 292,235) has a catch *k'*, designed to hold the loosely-pivoted lifting-lever from projecting rearwardly and in "the way of the operator" when not in working position. I am aware, also, that a corn-planter (Bapple, August 21, 1883, No. 283,459) has a wheel-scraper actuated by a non-locking foot-lever. I am aware, also, that a corn-planter (Runstetler, July 10, 1883, No. 281,204) has a stationary tubular axle in one piece bolted to the frame of the machine and "on which the wheels are journaled by means of revolving sleeves *C*, to which they are connected and on which they are laterally adjustable." I am aware, also, that a corn-planter (Hartsock, June 25, 1878, No. 205,264) provides radial marker-arms fastened on the axle in alignment with each other and having adjustable sleeved marker-heads. Hence I disclaim invention in those features which my present improvements have in common with all of the above-mentioned inventions.

I claim as my invention—

1. In a corn-planter, in combination, a rigid frame, two axle-boxes attached on opposite sides of said frame, a two-part revolving axle capable of being locked together as if in one piece, journaled in said boxes, and supported on two ground-wheels, a seed-delivery and hill-marking operating clutch-and-tappet mechanism adapted to engage a fixed clutch on one ground-wheel and revolve with it, and a hill-marking-operating clutch adapted to engage a similar fixed clutch on the opposite wheel of planter, for the purpose stated.

2. In a corn-planter, the dual hill-marking mechanism connected by the revolving two-part hollow axle carrying the ground-wheels fast on opposite ends of same, said axle being capable of revolving as one homogeneous axle or as two separate parts by means of toothed clutches on the abutting parts of the axle, one of said clutches being splined on one part of axle and the other clutch fast on its axle and adapted to move the one in or out of engagement with the other and fitted with lever and latch to hold one clutch out of engagement with the other, for the purpose stated.

3. In a corn-planter, in combination, a wheel *C*, having the clutch *V*, an axle *B*, journaled to revolve in a fixed box *Q* a plate *W*, mounted to revolve on said box *Q* and capable of engagement with said clutch *V*, a clutch *7*, fixed on said axle *B*, a clutch *8*, splined on axle *B'*, a fixed box *Q'*, in which said axle *B'* revolves and on which the plate *W'* is mounted to revolve, and a wheel *C'*, having the clutch *V'*, with which the plate *W'* is capable of engagement, substantially as and for the purpose stated.

4. In a corn-planter, the combination, with a revolving axle, two ground-wheels fast on the same, and means whereby the said wheels can be made to revolve at unequal speed or

the same speed at will, of the clutch-plates V V', fixed to said wheels, respectively, clutch-plates W W', sliding on the axle-boxes Q Q', respectively, the plate W having an annular series of holes w, tappets in said holes, and rollers on tappets, grain-delivery slide, means for connecting said tappets and said slide, and yoke X, secured to the circumferential groove in the said sliding clutch-plate, and 5 the plate W', having a similar yoke X, similarly seated to that on plate W, and both W and W' having levers Z, having latches z, racks 2, having notches 11, and links Y, connecting said levers and said yokes, for the 10 purpose stated.

5. In a corn-planter, a rigid frame A, sets of drag-bars N N, attached in any customary manner to the front transverse bar of said frame, and a cutter R, suspended on axle-bolt 20 r on hangers N' N', located between the forward ends of said drag-bars, said hangers being hinged between bars N N on the bolt r' and provided with a roller R' at the top end, in combination with the depressing-bars a a' 25 and a, attached to the under side of said frame, for the purpose stated.

6. In a corn-planter having a rigid frame A, the drag-bars N N, attached as customary to the front transverse bar of said frame, covering-blades S S, adjustably attached to said bars, a shoe L, fastened to and between the said drag-bars, and a cutter R, suspended on axle-bolt r on hangers N' N', said hangers being hinged between bars N N on the bolt r' and provided with a roller R' at the top end, in combination with the depressing-bars a a' 35 and a, attached to the under side of said frame, for the purpose stated.

7. In a corn-planter having a rigid frame, 40 in combination, the drag-bars N, attached by the bolts n to the front transverse bar of said frame, covering-blades S, having the adjustable clamps 19, the shoe L, having the top K and adjustable on the transverse bolt O, attachable to ends of strap P, having the series 45 of bolt-holes o, the bolt L', the rolling cutter R, hinged on the axle-bolt r, which is journaled in the hangers N', joined at their top ends by the bolt r'', carrying the friction- 50 roller R' and hinged on the bolt r' between said drag-bars, the forked rod N, hinged on said bolt r and guided at its threaded free end, which has the nut n'', by the staple n', and the depressing-bars a a and a', for the 55 purpose stated.

8. In a corn-planter, in combination, drag-bars attached as customary to the front bar of machine-frame, a furrow-opening shoe attached between said bars near their rear ends, 60 covering-blades at the rear ends, a rolling

cutter suspended on hangers between the forward ends of said drag-bars and provided with means by which the said cutters are automatically raised from the ground when the rear ends of said drag-bars are raised, and 65 with means also by which the depth of rolling cutter may be regulated, for the purpose stated.

9. In a corn-planter, the combination, with drag-bars attached as customary to the front 70 of frame, of a rolling cutter loosely suspended between the forward ends of said drag-bars and provided with a guide-rod forked at its rear end, which is hinged on the axle-bolt of said cutter and threaded and nutted at its 75 forward end, which moves freely in a loop or staple on the front of the frame, for the purpose stated.

10. In a corn-planter, a marker consisting 80 of a pole having a runner or head on one end, a shoulder on the other end, and an intermediate slot or eye, the said marker being held in operative position by vertical pins on opposite sides of frame adapted to engage the said eye, and a hook near transverse center 85 of machine-frame adapted to engage the said shoulder, for the purpose stated.

11. In a corn-planter, the combination, with two vertical pins, one of them projecting from upper surface of each side of planter-frame 90 at points near the front of said frame, and a ring or hook sliding crosswise of the machine on a bar fastened on the top of said frame forward of the axle and parallel to the same, of a pole having a marker-head at the ground 95 end, a recess or shoulder at the other end, and a slot or eye on pole intermediate between the ends of same to receive said pins, for the purpose stated.

12. In a corn-planter, the combination, with 100 pins M'' and the hook F''', of the marker M, having the head M', the eyebolt m, and the end m', for the purpose stated.

13. In a corn-planter, in combination, a tubular revolving axle in two parts capable of 105 being locked together as if in one piece and supported on ground-wheels fixed on the ends of said axle, a seed-delivery and hill-marking operating clutch - and - tappet mechanism adapted to engage a fixed clutch on one 110 ground-wheel and revolve with it, and a hill-marking-operating clutch adapted to engage a similar fixed clutch on the opposite wheel of planter, for the purpose stated.

In testimony of which invention I have 115 hereunto set my hand.

EDWIN R. PROCTER.
